EXTRACTION TOOL

David Van Dike Benfer, Marysville, Pa., assignor to
AMP Incorporated, Harrisburg, Pa.

Filed Feb. 3, 1970, Ser. No. 21,300

Term of patent 3½ years

Int. Cl. D8—02

U.S. Cl. D8—14

FIG. 1 is a perspective view of an extraction tool showing my new design;

FIG. 2 is a side elevational view of the tool shown in FIG. 1;

FIG. 3 is a top elevational view of the tool shown in FIG. 1;

FIG. 4 is an end elevational view of the tool of FIG. 2; and

FIG. 5 is another end elevational view looking from the opposite end of FIG. 2.

I claim:

The ornamental design for an extraction tool, substantially as shown.
